UNITED STATES PATENT OFFICE.

RUDOLPH A. SCHWAHN, OF EAU CLAIRE, WISCONSIN.

DESIGN FOR A TRACE-CARRIER.

43,558.

Specification for Design.

Patented Feb. 11, 1913.

Application filed October 2, 1912. Serial No. 723,643. Term of patent 14 years.

To all whom it may concern:

Be it known that I, RUDOLPH A. SCHWAHN, a citizen of the United States, residing at Eau Claire, in the county of Eau Claire and State of Wisconsin, have invented a new, original, and ornamental Design for Trace-Carriers, of which the following is a specification, reference being had to the accompanying drawing, forming part thereof.

Figure 1 is a perspective of the trace carrier, showing my new design. Fig. 2 is an elevation of the back side of the carrier.

I claim:

The ornamental design for a trace carrier, as shown.

RUDOLPH A. SCHWAHN.
